UNITED STATES PATENT OFFICE.

EDWARD L. BENEDICT AND ROBERT L. GLOSE, OF PITTSBURGH, PENNSYLVANIA.

REENFORCING FABRIC FOR CEMENTITIOUS SLABS.

Application filed May 29, 1924. Serial No. 716,693.

To all whom it may concern:

Be it known that we, EDWARD L. BENEDICT and ROBERT L. GLOSE, citizens of the United States, residing at Pittsburgh, in the county of Allegheny and State of Pennsylvania, have invented a new and useful Improvement in Reenforcing Fabrics for Cementitious Slabs, of which the following is a specification.

10 This invention relates to a reenforcing fabric for use with concrete, or other cementitious material, in roads, floors, and other generally similar structures.

One object of the invention is to provide 15 a fabric for reenforcing a cementitious monolith against variously directed stresses, which requires little or no assembling of the elements thereof in laying the fabric.

Another object of the invention is to provide 20 reenforcing fabric in which the various elements of the fabric fully perform the functions of supporting and mutually spacing the other elements thereof, so that the fabric may be laid entire without depending upon the material in which it is to be 25 embedded for support or spacing of the elements.

A further object of the invention is to provide 30 such rigidity in the support of the main reenforcing elements of the fabric, that such elements are held rigidly against any movement during pouring of the embedding material which might create a space adjacent such reenforcing elements; and to 35 so anchor the main reenforcing elements that vibration of the same in a slab of cementitious material is entirely prevented.

A still further object of the invention is to provide 40 a reenforcing fabric of the nature indicated, which is susceptible of ready adaptation to various uses, and conditions of use, without radical change in its general structure or sacrifice of the advantages noted above.

45 In the accompanying drawings Figure 1 is a plan view of one form of reenforcing fabric embodying the principles of the present invention; Figure 2 is a side elevation of the same; Figure 3 is a front elevation of the same; Figure 4 is an isometric view of the same; Figure 5 is a plan view of a special modified form of the fabric, showing such fabric with the omission of one reenforcing element thereof; Figure 6 is a side 50 elevation of this modified form of the fabric; Figure 7 is a plan view of the same 55

modified fabric, showing the same as laid prior to the addition of the cementitious material in which it is to be embedded, and showing the reenforcing element which is omitted from Figures 5 and 6; Figure 8 is a side elevation of the structure illustrated in Figure 7; Figure 9 is an end elevation of another modified form of the reenforcing fabric; Figure 10 is a side elevation of the same; Figure 11 is a cross sectional view through a roadway, showing the reenforcing fabric of Figures 1 to 4 inclusive embedded in the cementitious material of the roadway; Figure 12 is a cross sectional view through a roadway, illustrating one manner of adapting the form of fabric shown in Figures 1 to 4 inclusive to a roadway having a subgrade inclined toward the sides thereof; Figure 13 is a cross sectional view of a roadway illustrating another manner of adapting this form of the fabric to an inclined subgrade; Figure 14 is a fragmentary cross sectional view through a roadway, illustrating the adaptation of the structure shown in Figure 9 to an inclined subgrade; Figure 15 is an end elevation of a modified form of fabric, which corresponds generally to the form shown in Figures 1 to 4 of the drawings, but showing a modified positioning of a single main reenforcing element; and Figure 16 shows a further modification in the structure of Figures 1 to 4, which embodies an additional main reenforcing element.

In the simplest form of the device, as shown in Figures 1 to 4 inclusive of the drawings, the fabric comprises strand members or elements 1, which may be rods, bars or heavy wires; and stay members or elements 2, which extend transversely of the strand elements, and which are preferably wires, but may be bars or rods if so desired. The stay elements 2 are welded or tied to the strand elements 1 in any suitable manner. As shown, the stay elements 2 are offset from the horizontal plane of the strand elements 1 to form loops 3, having extremities 4 lying in a common plane parallel to the horizontal plane of the strand elements, or upper horizontal plane of the fabric.

According to one method of manufacturing the fabric, the stay elements 2 are originally disposed in substantially the same horizontal plane as, and at right angles to, the strand elements 1, and are welded or otherwise suitably secured thereto. These

stay elements are then offset a uniform vertical distance from their original horizontal plane, which is the upper horizontal plane of the fabric. As the offsetting of these loops is uniform throughout the fabric, the uniform spacing of the strand, or main reenforcing, elements is not affected by the formation of the loops in the stay elements.

In order to secure increased rigidity of the fabric, the loops 3 are offset at an angle to the vertical plane of each of the strand elements. As shown, adjacent loops of the same stay members or elements are offset at opposite angles to such plane to provide equally but oppositely inclined loops with their extremities 4 lying in a common plane parallel to the horizontal plane of the strand elements. The angular disposition of the loops 3 may be effected simultaneously with the offsetting of the stay wires to form the loops; and is effected by exerting forces to distort the stay wires both longitudinally of and at right angles to the horizontal plane of the strand elements, thus producing the inclined loops 3 as the resultant of such forces. It will be noted that all the extremities 4 of each row 5, that is all the loops lying between the same two strand elements, are inclined in the same direction and that the bends of any row or rows adjacent to a designated row extend at an opposite angle to those of the designated row. This effect of this staggered arrangement of the loops is to secure the maximum support afforded by a triangular base.

The modified form of fabric shown in Figures 7 and 8 inclusive of the drawings, combines the principles and advantages of the form described above with those of a transversely extending and relatively heavy reinforcing element, which is supported between the horizontal plane of the strand elements 1^a and the horizontal plane of the extremities 4^a of the loops 3^a.

The preliminary steps in the manufacture of this modified form of fabric are identical with those employed in manufacturing the form of fabric previously described. After such steps have been performed, however, alternate strand elements are pulled longitudinally in opposite directions to distort the loops 3^a. This distortion of the loops causes each loop to comprise a leg 6, and a leg 7 inclined at a lesser angle to the vertical plane of its strand element than the leg 6. It will be observed that the crossing of the legs 6 throughout the same stay element provides a seat for an additional horizontal reenforcing element 8, which may be a rod, bar, or heavy wire; and that this transversely extending reenforcing element is supported between the horizontal plane of the strand elements and the horizontal plane of the extremities 4^a of the loops of the stay elements.

With the arrangement of this modification, substantially the same effect is obtained whether the strand elements of the fabric be laid longitudinally or transversely of the roadway. This is the case because the additional reenforcing elements give a reinforcement extending at right angles to that of the strand elements.

The modification illustrated in Figures 9 and 10 of the drawings comprises the combination of two complete fabric members A and B. Of these the member A is identical with the form of fabric shown in Figures 1 to 4 inclusive; and comprises the stay members 2^a with loops 3^a and extremities 4^a the stay members being secured to strand, or main reenforcing, elements 1^a. The member B is also similar, but is made with the loops 3^a of the stay elements offset a lesser distance from the horizontal plane of the strand elements 1^a of the fabric member.

In assembling the members for laying of the fabric in constructing a roadway, the fabric member B is inverted and placed over the fabric member A in such manner that the inner side of the extremities 4^a of fabric member B rest on the strand elements 1^a of the fabric member A. The loops 3^a thus extend downwardly for a portion of the depth of the bends 3^a, and support the strand elements 1^a at points above the extremities 4^a of the bends 3^a.

This modification provides additional reinforcing elements, which extend parallel to the strand elements of the main fabric member, but which are spaced vertically from the horizontal plane of the extremities of the loops formed in the stay elements of the main fabric member, that is, they are spaced vertically from both the upper and lower horizontal planes of the completed fabric.

Figure 11 of the drawings shows the simplest form of the reinforcing fabric, that illustrated in Figures 1 to 4 inclusive, embedded in a concrete roadway, and extending completely across the same. This figure may also be taken as generally illustrative of one disposition of any of the modified forms of the fabric in a roadway.

In present day concrete road building it is considered good practice to have the road slab thicker along the sides of the road than at its center. As the road surface is generally crowned, or higher along the center of the road, this effect is secured by inclining the subgrade of the road downwardly toward both sides of the road.

Figure 12 of the drawings illustrates one manner of adopting the form of the device shown in Figures 1 to 4 inclusive to accommodate for this inclination, while maintaining the strand, or main reenforcing, elements substantially parallel to the surface of the

roadway. In this arrangement the fabric is laid with the strand elements 1 disposed transversely of the roadway. The inclination of the subgrade is here accommodated for by varying the angular disposition of the loops 3. As shown, the loops adjacent the sides of the road are spread to the least extent. Successive loops inwardly from both sides of the road are spread to a successively greater extent, so that the lower plane of the fabric, formed by the extremities 4 of the loops, is inclined to the perpendicular a degree substantially equal to the inclination of the subgrade of the roadway.

15 Figure 13 illustrates another manner of adapting the same initial form of fabric to the same condition of use. In such arrangement the strand, or main reenforcing, element of the fabric are disposed longitudinally of the roadway, as in Figure 11. The inclination of the subgrade is here accommodated for by varying the depth of the loops 3, to follow the inclination of the subgrade while maintaining the main reenforcing elements 1 substantially parallel with the surface of the roadway. Thus the loops adjacent both sides of the road are offset the greatest distance from the horizontal plane of the strand elements. Successive loops are offset to a successively lesser degree, so that the lower plane of the fabric, formed by the extremities 4 of the loops, is inclined to the perpendicular a degree substantially equal to the inclination of the subgrade of the roadway.

Starting with a fabric lying in a single horizontal plane, and with the strand elements spaced mutually at equal distances, the unequal offsetting of the loops will produce a grouping, or narrower spacing, of the strand elements along the sides of the fabric. If desired this effect may be avoided by spacing the strand elements initially an unequal distance, but the grouping as shown is preferable in roads, or portions thereof which are subjected to certain traffic conditions.

The fabric may also be arranged to accommodate for an inclination of the subgrade, while having the strand, or main reenforcing, elements extend longitudinally of the roadway. This is effected by progressively increasing the horizontal extension or distortion of successive loops 3 of each of the stay wires 2 transversely of the fabric. Obviously such arrangement does not alter the mutual spacing of the strand, or main reenforcing, elements.

Both ways of accommodating for an inclined subgrade may be readily effected during the manufacture of the fabric, and both illustrate the inherent adaptability of this fundamental form to various conditions of use. It should be observed that this adaptation does not sacrifice the advantage of the

triangular support given by the inclination of the offset loops of the fabric.

Figure 15 of the drawings illustrates a modified form of the fabric in which the strand, or main reenforcing, elements 1^e are welded to the legs or the loops 3^e formed in the stay elements at a point below the upper extremities 9^e formed by the offsetting of the stay elements. This provides a vertical spacing of the main reenforcing elements part way between the upper and lower horizontal planes of the fabric, and has the advantage, with certain classes of roadway, that the main reenforcing element serve to reinforce the slab partway of its depth.

Figure 16 of the drawings illustrates a modified form of the fabric in which two strand elements 1^f are supported close together on the same leg of a loop of the stay elements. As shown, both of these strand elements are relatively close to the upper extremities 9^f formed in offsetting the loops. This particular modification permits the use of lighter strand elements, while increasing the total cross sectional area and bonding area of the strand elements.

Both these modifications are in other respects identical with the fundamental form shown in Figures 1 to 4 of the drawings, and may be assumed to have the loops of the stay elements inclined to give the same triangular support.

It is of great importance that the structure of the fabric is such that it is self-supporting and self-spacing with respect to its various elements, so that the cementitious material to form the slab in which the reinforcement is embedded may simply be poured over the fabric when the latter has been placed in position. With materials of which this is not true, it is necessary, in order to space the reinforcement in the slab, that a layer of the cementitious material be first poured, the reinforcement laid thereon, and the pouring operation then completed. This operation involves a duplication of labor, and frequently requires the mixture of a fresh batch of the cementitious material.

The rigidity of the fabric structure is also of great importance. Any slight shifting of the fabric, due to inequality of weight distribution thereon, during or immediately after pouring of the cementitious material, would result in the formation of small spaces in the body of the slab. Such spaces would permit vibration of the fabric, with increasing pulverization of the enclosing material and relatively rapid disintegration of the slab.

Any possibility of such a condition is avoided by the inclination and staggering of the loops of the stay elements of the fabric, which maintain the fabric as a whole absolutely stationary through all ordinary contingencies incident to laying and pour-

ing. It may be noted in this connection that each stay element constitutes a triangular supporting element extending transversely of the strand elements. The form of the loops also results in a firm anchoring of the strand, or main reenforcing, elements in the slab, so that no vibration and play is initially permitted to produce an increasing cavity in and pulverization of the embedding material.

The form and arrangement of the loops of the stay wires also serve to securely anchor the main reenforcing elements in a finished slab against vibration under the impacts delivered by traffic passing over the slab. This avoids any possibility of the wearing of cavities in the cementitious material of the slab by vibration of the reenforcing members therein.

It is also to be noted that the shear stresses in a concrete block in which this fabric is embedded are crossed by the stay elements because of their angular position and staggered arrangement.

As numerous modifications in the form and arrangement of the elements of the fabric, other than those illustrated and described herein, may be made without departing from the principles of the present invention, the scope of the invention is to be restricted only by the limitations contained in the claims appended hereto.

What we claim is:

1. A reenforcing fabric for use with cementitious materials comprising a plurality of strand elements disposed in the same horizontal plane, and transverse stay elements interconnecting said strand elements; each of the stay elements having loops offset at an angle to the horizontal plane of the strand elements, and alternate loops of each stay element being offset at opposite angles, to provide distributed supporting means for the entire fabric during the pouring of a concrete slab and to secure a maximum distribution of metal throughout the body of such slab.

2. A reenforcing fabric for use with cementitious materials comprising a plurality of strand elements disposed in the same horizontal plane, and transverse stay elements interconnecting the strand elements and having loops offset from the horizontal plane of the strand elements at such angles that each stay element constitutes a transverse triangular support for the strand elements of the fabric.

3. A concrete roadway having a reenforcing fabric embedded therein, said fabric

comprising a plurality of reenforcing strand elements extending longitudinally of the roadway and elements of greater flexibility secured to the strand elements and extending transversely of the strand elements and the roadway, each of said transverse elements being formed with loops offset at an angle to the surface of the roadway and the transverse elements being so arranged that the loops of the same element have their horizontal extension in opposite directions in alternate intervals between strand elements.

4. A concrete roadway having a reenforcing fabric embedded therein; said fabric comprising strand elements extending longitudinally of the roadway, and stay elements secured to the strand elements and extending transversely of the strand elements and the roadway; the stay elements having loops offset at an angle to the surface of the roadway, and successive loops of each stay element being of graduated vertical extent transversely of the roadway to accommodate the fabric to an inclined subgrade in the roadway.

5. A concrete roadway having a reenforcing fabric embedded therein; said fabric comprising strand elements extending longitudinally of the roadway, and stay elements secured to the strand elements and extending transversely of the strand elements and of the roadway; the stay elements having loops offset at an angle to the surface of the roadway and so arranged that the loops of the same element have their horizontal extension in opposite directions in alternate intervals between strand elements, and successive loops of each stay element being of graduated vertical extent transversely of the roadway to accommodate the fabric to an inclined subgrade in the roadway.

6. A reenforcing fabric for use with cementitious materials comprising a plurality of strand elements disposed in the same horizontal plane, and transverse stay elements interconnecting the strand elements, said stay elements being formed with loops offset from the horizontal plane of the strand elements and extending longitudinally of the strand elements, the loops in adjacent intervals between strand elements extending in opposite longitudinal directions.

In testimony whereof, we hereunto set our hands.

EDWARD L. BENEDICT.
ROBERT L. GLOSE.
